UNITED STATES PATENT OFFICE.

WILLIAM J. NORRIS, OF REYNOLDSVILLE, PENNSYLVANIA.

ENVELOP-FASTENER.

1,087,049.

Specification of Letters Patent.

Patented Feb. 10, 1914.

Application filed March 12, 1912. Serial No. 683,326.

To all whom it may concern:

Be it known that I, WILLIAM J. NORRIS, a citizen of the United States, residing at Reynoldsville, in the county of Jefferson 5 and State of Pennsylvania, have invented new and useful Improvements in Envelop-Fasteners, of which the following is a specification.

This invention relates to envelop fasteners 10 and particularly to safety envelops.

The principal object of the invention is to provide a simple and efficient envelop used in connection with a novel type of fastener which prevents access to the envelop with- 15 out destroying or mutilating the envelop.

A further object of the invention is the provision of a novel, simple and efficient fastener which may be cheaply constructed and which may be either arranged so as to 20 fasten the envelop permanently or so that the envelop may be readily opened and re-fastened when necessary.

Further objects of this invention will appear as the following specific description is 25 read in connection with the accompanying drawings, which form a part of this application, and in which:—

Figure 1 is an elevation of an envelop used for second class mail matter showing 30 the flap element of the fastener ready for insertion in its coacting element on the body of the envelop. Fig. 2 is an enlarged section taken longitudinally through the fastener elements on the line 2—2 of Fig. 1.

Referring to the drawings, 1 represents an ordinary shipping envelop best adapted to carrying second class matter and the like and is provided with the usual closing flap 2. Secured to the body of the envelop by 35 means of the prongs 3 which are struck up therefrom is a plate 4 having a tongue engaging loop 5 punched up from its body a sufficient distance to permit the passage of a locking extension 6 which is carried by a

plate 7 secured to the flap 2 by the prongs 45 8 which are also punched up from its body. This extension 6 is provided with an upwardly bent spring tongue 9 adapted to engage against the loop 5 so as to lock the extension within the loop, as shown in Fig. 50 2. The rear end of the flap plate 7 is provided with a rolled extension 10 which can be conveniently engaged by the finger for withdrawing the extension 6 from the loop when the tongue has been depressed out of 55 engagement with the loop 5. Preferably, the locking prongs extend through the body of the envelop and flap and also through reinforcing disks 11 secured to the inside of the body and the inside of the flap. This 60 prevents the fasteners from tearing out when any strain is placed thereon.

What is claimed is:—

In an envelop fastener, the combination with a plate for connection with the body of 65 the envelop, of a second plate for connection with the sealing flap of the envelop, a loop carried by the first plate, an extension on the second plate and adapted to pass through the said loop, and a spring-like 70 locking tongue struck from the outer end of the said extension and projecting longitudinally toward the inner end thereof, with the tongue inclined from the point of its formation and lying out of the plane of the 75 extension so that its free end will abut against an edge of the loop after the said extension has been passed therethrough, the said tongue being struck from the central portion of the outer end of the said exten- 80 sion.

In testimony whereof I affix my signature in presence of two witnesses.

WILLIAM J. NORRIS.
